To all whom it may concern:

Be it known that I, Lawrence J. Kihm, a citizen of the United States of America, residing at Pittsburgh, county of Allegheny, and State of Pennsylvania, have invented a new, original, and ornamental Design for a Toilet Bottle, of which the following is a specification, reference being had to the accompanying drawing, forming a part thereof.

Figure 1 is a front view of a toilet bottle showing my new design.

Figure 4 is a top view.

I claim:

The ornamental design for a toilet bottle as shown.

LAWRENCE J. KIHN.
